AUTOMATIC TELEPHONE-EXCHANGE SYSTEM.

1,151,542.

Specification of Letters Patent. Patented Aug. 24, 1915.

Application filed December 20, 1906. Serial No. 348,769.

To all whom it may concern:

Be it known that we, ALEXANDER E. KEITH and TALBOT G. MARTIN, both citizens of the United States of America, and residents of Chicago, Cook county, Illinois, have invented a certain new and useful Improvement in Automatic Telephone-Exchange Systems, of which the following is a specification.

10 Our invention relates to automatic telephone exchange systems, but more particularly to party line exchanges, and especially to common battery exchanges in which the party lines are provided with individual switches for automatically trunking calling subscribers into connection with idle first-selectors, our invention broadly contemplating a system characterized by these features, in combination with the feature of a lock-out arrangement for each party line subscriber, whereby one subscriber cannot interfere with another in the use of a party line.

To the foregoing and other useful ends, our invention consists in matters hereinafter set forth and claimed.

In the accompanying drawings, Figure 1 is a diagrammatic view representing an established connection of the switching apparatus involved when one subscriber calls another subscriber on his own line. The subscriber's line terminates in the line switch A at the central office, where the battery B is located that provides current for both calling and talking purposes. As shown, the said battery has its positive terminal preferably grounded at G. The said line switch is represented as having connected with a selector-switch C, and the selector with the connector D, the latter having called back upon the calling line across which are bridged the substations E, F and H; E being the calling station and H the called station. The central office battery B is shown in the various drawings, but there is in fact but one battery. The line switch, being of the general type described in patent application Serial No. 311,327, is controlled for selective purposes by the so-called master switch I. The line switches are all arranged in groups of, usually, one hundred, each hundred being controlled by an allotted master switch. Fig. 2 is also a diagrammatic view showing the more important operative details of the line switch

A and of the master switch I and the circuit connections between said switches. Fig. 3 is a diagram of the connector.

The substation may be of any suitable or approved type. The substation E, for instance, like all the other substations in the system, may be of the general type described in patent application Serial No. 278,901. The substation E, for instance, is provided with a receiver 2 and a switch-hook 3, which latter has radiating from its body a number of cam arms 4, 5 and 6, the cam arm 6 being provided with an insulating tip 7. Said hook is suitably pivoted on the so-called substation keyboard frame which carries most of the mechanical details of the telephone. As usual, the switch-hook is raised or lowered whenever the receiver is removed or restored to its place. The said hook is raised or lowered to accomplish certain switching operations to be disclosed, and for controlling certain mechanical details that will be hereinafter described. Furthermore, said substation has a transmitter 8, a ringer 9, and an induction-coil 10 having primary and secondary windings 11 and 12, respectively; also a couple of condensers 13 and 14, a signaling device composed of a push-button 15, a spring 16, and two contact points 17 and 18, whereby one side of the main line may be grounded; and in addition a relay 19 under the control of which are the springs 20, 21, 22 and 23. When the switch-hook is down the cam arm 5 is held in contact with the spring 24, whereby said spring is at such time retained in a downwardly flexed condition. Said spring and cam arm are, therefore, normally in contact, and in this way a circuit is completed from the line through the ringer 9, which circuit includes, beside the ringer 9, the ringer circuit spring 24 and condenser 13.

Associated with the ringer circuit spring 24 are two sets of springs 26 and 27, and 28 and 29. The members of each of these sets, when left to their own tension—that is, when the switch-hook is up—engage with each other, the springs 26 and 27 being in contact, and the springs 28 and 29 being also in contact; and whenever the switch-hook depresses the spring 24 the springs 27 and 29 separate from the springs 26 and 28, respectively. The cam arm 6 controls the springs 30, 31, 32 and 33 of which the mem-

bers 30, 31 and 32 are normally retained out of engagement with each other, and the spring 32 in contact with the fourth spring 33; but when the switch-hook is up the first 5 three springs are forced together by the said cam arm 6. Furthermore, while the switch-hook is down the springs 34 and 35 are kept apart by the said cam arm 6, but after the switch-hook rises and the dial is turned, the 10 said springs flex into contact. There are three other springs 36, 37 and 38 under the control of the cam arm 4, which springs are known as the release springs, and which are forced into engagement by the said cam arm 15 when the latter engages a laterally projecting piece 39 at the upper extremity of the spring 38. However, when the switch-hook nears its lowermost position said arm disengages from said spring and permits the 20 said release springs to again disengage. The calling device in this substation comprises an impulse wheel 40 which is provided with so-called vertical impulse teeth 41 and with a rotary impulse tooth 42, the 25 former being adapted to operate the vertical impulse spring 43, and the latter the rotary impulse spring 44 with regard to the ground post 45, whereby ground impulses are transmitted to the line for operating 30 the central office apparatus. Normally, the impulse wheel and dial are locked by the locking cam 46 and the dog 46', the former normally resting in front of a pin on the extremity of the dog 46' so that it is impossible to rotate the dial. The substation relay 19 is suitably mounted upon the keyboard or switch-frame. This relay is provided with an armature 47 by means of which, when the relay is magnetized, the 40 springs 20 and 22 are separated from the springs 21 and 23, respectively. Furthermore, said relay has on its under side an armature locking device that consists preferably of a metal piece 48 which is riveted 45 to a spring 49 that is fastened to the rear of the relay frame. The front end of said metal piece is bent upwardly and also at a right angle to the front; and whenever the armature 47 is attracted by the magnet the 50 tension in the spring 49 forces the metal member upwardly until the angled section rises in front of the armature 47, locking the latter in its attracted position, as shown at substation F. The switch-hook also carries a small link rod 50 that extends to the 55 front of the relay. The lower end of said link works in front of the armature 47 and is bent horizontally at a right angle and in a plane parallel to the plane of the armature. 60 When the switch-hook is depressed, the said link 50 descends far enough to drive the lock 48 below the edge of the armature 47, which latter then, if the magnet is not energized, resumes its normal position, as shown 65 at substation E in Fig. 1. When the said

armature is restored the relay springs 20 and 21, 22 and 23, of course, reengage.

The line switch A is built upon a suitable frame and comprises a plunger 51 and a plunger arm 52. It is also equipped with a cut-off relay 53 and trip magnet 54 and the switch release magnet 55. The said magnets may be secured to the switch frame by any means known to the art. The said release magnet 55 is provided with an armature 56 that is pivoted to a pin 57, the latter rising from the frame of the switch. This armature is normally held away from the pole pieces of the magnet by any suitable spring 58. The said armature 56 carries 75 pivotally secured to its end a second armature 59 that is controlled by the trip magnet 54 and which is normally held away from the pole pieces of the said trip magnet by a suitable spring 60. The pin 61, about 80 which the armature 59 oscillates, is carried on a bifurcated terminal of the armature 56. The plunger 51 is pivotally secured by a pin 62 to the plunger arm 52, which latter is in turn pivotally held in place by a pin 63. The said line switch is provided with a bank of terminals, usually ten in number, only one of which is shown at J. As shown in Fig. 2, the said terminal J is distorted 85 from its true position with respect to the swing of the plunger 51. The terminal J comprises the springs 64 and 65, 66 and 67, 68 and 69, 70 and 71. The said springs are normally disconnected from each other, and when the plunger 51 operates are driven 90 into contact in the following order: 64 and 65, 66 and 67, 68 and 69, and 70 and 71. Normally, the plunger 51, however, is retained out of engagement with the line switch bank and in engagement with the plunger-controlling shaft 72, which latter is operated by the master switch I. The said plunger is thus held by the armature 59 of the trip magnet 54, which latter is provided with a terminal 73 adapted to engage 95 the rear terminal 74 of the plunger arm 52 in opposition to the tension of the plunger arm spring 75. The cut-off relay 53 is provided with a couple of springs 76 and 77 for controlling the energizing circuit 100 of the trip magnet 54.

The operation of the line switch A in general is as follows: When the subscriber removes his receiver from the switch-hook, as the latter rises a preliminary impulse is sent from the substation that energizes the trip magnet 54 for a moment, whereby the armature 59 is attracted and the catch 73 disengaged from the plunger arm 52; then the spring 75 rotates the said arm 52 about the pin 63, and if the position of the plunger shaft 72 is such that the plunger 51 is opposite the terminal J the said plunger 51 is thrust between the terminal springs 71 and 115 74, whereby the terminal springs are closed 120 125 130

into contact, as already described. The plunger shaft 72 is provided with a longitudinal channel 77 in which all idle plungers normally rest. When the plunger is brought into use it may be restored by a momentary energization of the release magnet 55, which occurs when the subscriber hangs up his receiver and grounds both of his line conductors simultaneously. In such event the release magnet attracts the release armature 56, whereby the armature 59 is raised sufficiently to permit the catch terminal 73 to drop into normal engagement with the plunger arm 52; then when the release magnet deenergizes, the plunger 51 is withdrawn from the bank and carried into engagement with the shaft 72. It will be understood that the rotary motion of the plunger shaft is a backward and forward motion, and at no time does the channel 77 pass without the range of the rear terminal 78 of the plunger 51.

The master switch I is provided for operating the plunger shaft 72 and for controlling certain circuits that will be disclosed. It is a comparatively simple switch, having the following details: a motor magnet 79 for operating the ratchet wheel 80, a differential relay 81 and an auxiliary relay 82, the former controlling the energizing circuit of the motor magnet 79, and the latter the energizing circuits of all trip magnets 54 of line switches controlled by said master switch. The said master switch also has a bank K comprising a plurality of individual contact segments *a* and a metallic segment 83 common to the said segments, as shown in Fig. 2. The wiper 84 is adapted to remain in constant engagement with the bank K, and to at all times maintain some one of the segments *a* in electrical connection with the common segment 83. The wiper 84 is operated in a step-by-step manner by the ratchet wheel 80, through the medium of a cam member 85 rigidly secured to the said wiper 84 and adapted to successively engage the pins 86, 87, 88 and 89 upon the said ratchet wheel 80. The said wiper 84 and cam member 85 are, as shown, rigidly connected to one head of the plunger shaft 72. The motor magnet 79 is provided with an armature 87 upon the end of which there is suitably secured a pawl 90. Each time that the said magnet is energized the pawl 90 engages the ratchet wheel 80, advancing the latter one step. It will therefore be noticed that as the ratchet wheel 80 advances in a counter-clockwise direction, the wiper 84 advances step-by-step from right to left; and when the pin 86, for instance, clears the cam 85 the retracting spring 91 restores the wiper 84 to its first position at the right of the bank K in engagement with the first segment 92. The said motor magnet 79 is provided with a couple of interrupter springs

93 and 94 that are included in the energizing circuit of the said motor magnet, which energizing circuit also comprises the springs 95 and 96 controlled by the differential relay 81. Therefore, whenever the differential relay 81 is energized the springs 95 and 96 are pressed into contact and the motor magnet 79 operates step-by-step as long as the differential relay 81 remains energized. Furthermore, it is assumed that the terminal 75 J of the line switch A is the first terminal of the line switch bank, and therefore the plunger 51 is retained in front of said terminal by the plunger shaft 72 whenever the master switch wiper 84 is in engagement 80 with the bank segment 92; but as the motor magnet 79 advances the wiper 84 onto the second segment 97, all idle plungers are carried opposite the next terminal of the line switch bank. It should be noted that 85 in each line switch bank all of the springs 70 are permanently connected and may be made of one common piece; the springs 69 are, however, individual—that is, there is one separate and distinct spring for every 90 bank terminal J, there being, therefore, ten in all in the bank. The springs 68, 64, 71 and 66, like the springs 70, are also common, and the springs 65 and 67, like the springs 69, are individual. For every bank terminal J there is a trunk line of three conductors 98, 99 and 100 leading to a selector, and there is also a normal trunk line comprising the conductors 101, 102 and 103 leading to the connector banks. The subscriber's line conductors 104 and 105 terminate in the springs 64 and 66 which, as has been stated, are common springs. The vertical and rotary trunk conductors 98 and 99 pass through the vertical and rotary private normal relays 106 and 107, respectively, and these relays control the connection between ground and the private normal conductor 103 through the medium of the springs 108, 109, 110 and 111. When the subscriber operates the line switch A, and the plunger engages the terminal J, the subscriber's line conductors 104 and 105 are extended through the private normal relays 106 and 107 to the vertical and rotary trunk conductors 98 and 99, and thence to the selector switch C.

The first-selector may be of any suitable or approved type, such as the selector described in United States Patent No. 815,321, granted March 13, 1906, to Keith, Erickson and Erickson. It comprises a switch-shaft (not shown) to which the vertical and rotary line wipers 112 and 113 and the private wiper 114 are attached. The said switch-shaft is controlled by the calling subscriber through the medium of the vertical and rotary line relays 115 and 116. The former is adapted to operate the vertical magnet 117, which magnet is designed to impart to the switch- 120 125 130

shaft its vertical movement. The private magnet 118 is controlled by the rotary line relay 116, said private magnet having control of the well-known side switch that comprises the side switch wipers 119, 120, 121 and 122. When the said private magnet 118 permits the side switch to pass to second position, the rotary magnet 123 becomes operative, which magnet is designed to give the switch-shaft its rotary or circular movement. The vertical and rotary line relays 115 and 116 are adapted to control the release magnet 124 before the side switch passes to third position, but the selector being of the trunk-release type, when the side switch passes to third position the release magnet 124 is controlled from the next switch by means of the back-release relay 125 in a well-known manner.

20 The connector switch D is of the general type described in United States Letters Patent No. 815,176, granted March 13, 1906, to Keith, Erickson and Erickson. The connector switch-shaft 126' carries the switch-shaft wipers 126, 127 and 128. The said connector is controlled by the calling subscriber through the medium of the vertical and rotary line relays 129 and 130. The vertical line relay 129 is employed for controlling both the vertical and rotary magnets 131 and 132, which magnets 131 and 132 in turn impart to the switch-shaft and wipers their vertical and rotary movements. The rotary line relay 130 controls the private magnet 133, which latter in turn controls the position of the connector side switch L, which side switch is provided with the wipers 134, 135, 136 and 137. The connector side switch, like the side switch of the first-selector, normally rests in a position known as the first position of the side switch, and may be shifted to second and third positions by the operation of the private magnet. The vertical and rotary line relays 129 and 130 may be used conjointly by the calling subscriber for energizing a release magnet 138. The energizing circuit for said release magnet is retained normally open by the connector differential relay 139; which relay is provided with two windings 140 and 141. When the said differential relay energizes it closes the connection between the release magnet and the non-grounded terminal of the battery. Said differential relay also controls the energizing circuit of the rotary back-bridge relay 142 and of the vertical back-bridge relay 143 when the called subscriber has answered. In addition, the connector has the usual ringer relay 144. Through the medium of the ringer relay springs 145, 146, 147, 148, 149 and 150, said ringer relay is adapted to disconnect the calling subscriber's line from the called subscriber's line, and to bridge the latter across the ringer generator 151. The said ringer relay

has in addition a couple of springs 152 and 153, whereby when the said ringer relay is energized the normal bridge across the main line that exists through the vertical and rotary line relays 129 and 130 is opened in 70 order to prevent ringing current from interfering with the connector when the said connector calls back on the calling line. In the exchange there is also a busy signaling machine M (Fig. 1) comprising an induction-coil 154 having a primary winding 155 and a secondary winding 156.

The operation by which one subscriber calls another is as follows: To call the number 310, for example, the subscriber at substation E or #110 operates his calling device once for each digit. The preliminary impulse for operating the line switch A, however, precedes the operations of the calling device corresponding to the digits. Said impulse is transmitted when the hook spring 155' engages the ground spring 156', as the subscriber removes his receiver 2 from the switch-hook 3. As a result the trip magnet 54 of the line switch A is energized by a flow of current from ground G¹ to the springs 156' and 155', thence to the switch-hook 3 and to the rotary line conductor 105, conductor 157 (Fig. 2), cut-off relay springs 76 and 77 to the trip magnet 54, thence through said trip magnet to the conductor 158, auxiliary relay springs 159 and 160 to the battery lead 161, thence through battery B to ground G. As soon as the trip magnet 54 energizes, the armature 59 is attracted and the plunger 51 is liberated and thrust into the bank terminal J by the spring 75. At the instant that the said plunger 51 enters the said bank position J, the following springs are pressed into contact: 64 and 65, 66 and 67, 68 and 69, 70 and 71. The engagement of the springs 70 and 71 establishes a circuit from ground G² by way of the normal conductor 103 to the connector private bank contacts corresponding to the line that terminates in the line switch A, whereby a guarding potential is set up to prevent any calling subscriber from calling the said line after the calling operation has begun, as explained. The circuit over which the said guarding potential is established extends from ground G² through the private normal relay springs 111 and 110, conductor 162, bank springs 71 and 70 to the private normal conductor 103, thence to the connector private banks. The closure of connection between the springs 68 and 69 also establishes a guarding potential at the master switch bank contact 92 over the following circuit: from battery B to the battery lead 161, thence to the release magnet 55 and through the said magnet and springs 68 and 69 over the conductor 163 to the said contact point 92. It will be understood that the bank terminal J, being the first 120

bank terminal of the line switch bank, corresponds to the first segment 92 of the master switch bank K. At the instant that the said guarding potential is established the 5 master switch wiper 84 is resting upon the contact point 92, thereby closing a circuit between the said contact and the common plate 83 of the bank K, whereby an energizing circuit is established for magnetizing 10 the auxiliary relay 82 and the differential relay 81 of the master switch. The current through the said relays flows from the said contact 92 through the wiper 84 to the common segment 83, thence over the conductor 15 164 through the auxiliary relay 82, and through the winding 165 of the auxiliary relay 81 to ground G³. When the differential relay 81 attracts its armature the differential relay springs 95 and 96 are pressed 20 into contact, thereby closing the energizing circuit for the motor magnet 79 from ground G⁴ through the said springs 96 and 95 to the motor magnet 79, thence through the said magnet and through the interrupter 25 springs 94 and 93 to the battery lead 161, and through battery B to ground G. The motor magnet then operates to rotate the ratchet wheel 80 one step for advancing the plunger shaft 72 one step and the master 30 switch bank wiper 84 one step also into engagement with the second segment 97. The plunger shaft 72, when thus advanced one step, carries all idle plungers that are in engagement with the said shaft opposite 35 the next bank terminal (similar to the terminal J), which corresponds to the segment 97 of the master switch bank K. If there should be a guarding potential at the bank segment 97 of the master switch the differential relay 81 will remain energized after 40 the motor magnet armature 87' returns to normal position and again closes connection between the springs 93 and 94, and as a result the motor magnet 79 is again operated, 45 whereby the plunger shaft 72 and the master switch wiper 84 are advanced another step. This process continues as long as the wiper 84 continues to find segments with guarding potentials. As soon as an idle 50 segment is found, the energizing circuit through the differential relay 81 is broken, at which time the said relay in turn permanently breaks the energizing circuit for the motor magnet 79 until the next subscriber makes a call.

It will be noticed that the energizing circuit for the trip magnet 54 is controlled by the auxiliary relay 82. As a matter of fact, and as already stated, all the trip magnets 55 of the line switches in the same group are controlled by the said springs 159 and 160, whereby, when the auxiliary relay 82 is energized, no line switch will be able to trip and seize a trunk line until the wiper 84 of the master switch finds an idle segment.

The object in thus arranging the circuits of the trip magnets is to prevent any subscriber from tripping in his allotted line switch onto a busy trunk if he should call while the auxiliary relay 82 is energized, 70 and, of course, while the wiper 84 is passing over busy contacts. The engagement of the said line switch bank springs 68 and 69; furthermore, establishes a connection between the release magnet 55 of the line 75 switch A and the spring 166 of the back-release relay 125 of the selector C (Fig. 1), and when the back-release relay presses the said back-release relay spring 166 onto the ground spring 167 an energizing circuit is 80 established through said release magnet.

The closure of connection between the springs 64 and 65 extends the calling subscriber's vertical line conductor 104 to the vertical private normal relay 106, and 85 through the said relay to the vertical trunk conductor 98, and thence to the side switch wiper 119 of the first-selector C. The closure of contact between the springs 66 and 67 in a similar manner extends the subscriber's rotary line conductor 105 to the rotary private normal relay 107, and through the said relay to the rotary trunk conductor 99, and thence to the side switch wiper 120 of the selector C. The subscriber has thus established connection with the selector C and is 90 ready to begin operating his calling device for the first digit.

The first digit being 3, the subscriber operates his dial accordingly, grounding the vertical line conductor 104 each time that the spring 43 is pressed onto the ground post 45. As a result the vertical line relay 115 of the first-selector C is energized by a flow of current from the substation ground G¹ through 100 the substation relay springs 22 and 23, to the ground post 45, thence through the spring 43 to the vertical line conductor 104, line switch bank springs 64 and 65, vertical private normal relay 106, vertical trunk conductor 98, side switch wiper 119 of the selector C, contact point 168, vertical line relay 115 to the battery lead 161, thence through 105 battery B to ground G. Each time that the vertical line relay 115 energizes, the line relay spring 169 is pressed onto the ground spring 170. The vertical magnet 117 is thereby energized, and the wipers 112, 113 and 114 of the selector C are raised to the third bank level opposite the first contact of 110 said level. The energizing circuit for the said vertical magnet 117 extends from ground G¹⁴ through the springs 170 and 169, private springs 172 and 173 to the vertical magnet 117, thence to the battery lead 161, and through battery B to ground G. The spring 44 is then pressed onto the ground post 45, grounding the rotary line conductor 105 and energizing, therefore, the rotary line 115 relay 116 of the selector C. The energizing 120 circuit for the said vertical magnet 117 extends from ground G¹⁴ through the springs 170 and 169, private springs 172 and 173 to the vertical magnet 117, thence to the battery lead 161, and through battery B to ground G. The spring 44 is then pressed onto the ground post 45, grounding the rotary line conductor 105 and energizing, therefore, the rotary line 125 relay 116 of the selector C. The energizing 130

current extends from ground G¹ to the rotary line conductor 105, thence it flows through the line switch bank springs 66 and 67, rotary private normal relay 107, rotary 5 trunk conductor 99, side switch wiper 120 of the selector C, contact point 171' to the rotary line relay 116, thence through said relay to the battery lead 161, and through battery B to ground G. The rotary line relay, upon operating, presses the line relay spring 171 onto the ground spring 170, thereby establishing a circuit through the 10 private magnet 118 from ground G¹⁴ through the springs 170 and 171 to the private 15 magnet 118 and through the said magnet to the battery lead 161, thence through battery B to ground G. The private magnet, upon energizing and deenergizing, permits the selector side switch to pass from first 20 to second position, permitting the side switch wipers 121 and 122 to engage the contact points 174 and 175, respectively.

The closure of connection between the side switch wiper 122 and the contact point 175 25 sets up a magnetizing circuit for the rotary magnet 123 from ground G' to the contact point 175, through the side switch wiper 122, interrupter spring 176, rotary magnet 123 to the battery lead 161, thence through battery B to ground G. The said rotary magnet 123 then operates to rotate the wipers 112, 113 and 114 of the selector C into engagement with a trunk line leading to some 30 idle connector switch and, in the particular case under consideration, to the connector switch D. If the wipers have to pass over busy trunk lines, the private wiper 114 engages a grounded contact point and the private magnet 118 remains energized, locking 35 the side switch in second position. The energizing circuit for said private magnet extends from an occupying switch (not shown) to the private wiper 114, thence over the conductor 177, and through the back-release 40 relay 125 to the side switch wiper 121, contact point 174, private magnet 118, thence through said magnet to the battery lead 161, and through battery B to ground G. The private magnet 118, upon thus becoming energized, locks the side switch wiper 122 in engagement with the grounded contact point 175, whereby the rotary magnet 123 will be energized step-by-step until the wipers are carried beyond the last busy trunk line. At 45 the instant that the private wiper leaves the last busy contact point, the energizing circuit through the private magnet 118 is destroyed, and as a result the selector side switch passes to third position. If, however, there are no busy trunk lines, the private magnet 118 releases the side switch to 50 third position as soon as the wipers are carried into engagement with the first trunk line. As soon as the side switch passes to 55 third position, as stated, the subscriber's line

conductors 104 and 105 are extended to the idle connector switch which, in this case, it is assumed is the connector switch D. The extension of the line occurs as soon as the side switch wipers 119 and 120 engage the contact points 178 and 179, respectively. Not only is the subscriber's line thus extended, but a guarding potential is established at the private wiper 114; when the side switch wiper 121 passes onto the grounded 75 contact point 180, for protecting the seized trunk line from interference by other calling subscribers. This guarding potential is established from ground G to the contact point 180, thence through the side switch 80 wiper 121 and through the back-release relay 125 to the private wiper 114. It will be necessary, of course, that the energizing circuit for the rotary magnet 123, to which reference has already been made, be destroyed 85 when the idle trunk line is seized, and therefore when the side switch wiper 122 leaves the grounded contact point 175 this energizing circuit is broken. In the foregoing the energizing circuits for the vertical and 90 rotary line relays 115 and 116 have comprised the private normal relays 106 and 107, as described, but the energization of said relays so far has played a part of no 95 significance.

The second digit of the number being 1, the calling subscriber operates his dial again accordingly, as a result grounding the vertical line conductor 104 when the spring 43 meets the ground post 45. The vertical line 100 relay 129 of the connector switch D is, therefore, energized by a flow of current from the substation ground G' to the vertical line conductor 104, thence through the line switch bank springs 64 and 65, vertical private normal relay 106, vertical trunk conductor 98, side switch wiper 119 of the selector C, contact point 178, vertical line wiper 112, vertical trunk conductor 181, vertical line relay 129, winding 140 of the differential relay 139 to the battery lead 161, thence through battery B to ground G. This circuit comprises the winding 140 of the differential relay 139, so that the said differential relay energizes simultaneously 115 with the vertical relay 129, but the said energization produces no effect at this time. The vertical line relay 129, upon energization, presses the line relay spring 182 into engagement with the ground spring 183, as a result operating the vertical magnet 131 by the establishment of a circuit from ground G' through the springs 183 and 182, private springs 184 and 185, side switch wiper 134, contact point 188', vertical magnet 131, thence through battery B to ground G. The vertical magnet 131, as is well understood, then operates to raise the switch-shaft 120 wipers 126, 127 and 128 of the connector D to the desired bank level, as disclosed in the 125 130

said connector patent. The connector having been thus operated, when the rotary spring 44 engages the ground post 45 the rotary line conductor 105 is grounded once, 5 energizing the connector rotary line relay 130 over the following circuit: from ground G' at the substation to the rotary line conductor 105, through the line switch bank springs 66 and 67, rotary private normal 10 relay 107, rotary trunk conductor 99, side switch wiper 120 of the selector C, contact point 179, rotary line wiper 113, rotary trunk conductor 186, rotary line relay 130, differential relay winding 141, ringer relay 15 springs 152 and 153, back-bridge relay springs 187 and 188 to the battery lead 161, thence through battery B to ground G. The differential relay 139 again energizes, but still to no effect. The rotary line relay 130, 20 however, presses the line relay spring 189 onto the ground spring 183, as a result energizing the private magnet 133. The circuit established extends from ground G' through the springs 183 and 189, private magnet 133, 25 conductor 190, rotary back-bridge relay springs 187 and 188 to the battery lead 161, thence through battery B to ground G. The private magnet, upon deenergizing, permits the connector side switch to pass to second 30 position, shifting the side switch wiper 134 into engagement with the contact point 191. The rotary magnet 132 is thus substituted for the vertical magnet 131 to the control of the vertical line relay 129.

35 The third digit of the desired number being 0, the calling subscriber operates his dial to ground the vertical line conductor 104 ten times. As a result the vertical line relay 129 of the connector D is energized ten 40 times, and the line relay springs 182 and 183 operated accordingly. The rotary magnet 132 is energized over a circuit extending from ground G' through the line relay springs 183 and 182, private springs 184 and 185, 45 side switch wiper 134, contact point 191 and the rotary magnet 132 to the battery lead 161, thence through battery B to ground G. The said rotary magnet then operates to rotate the shaft wipers 126, 127 and 128 step- 50 by-step onto the tenth contact of the first level of the connector bank, from which terminal leads a trunk line that extends back to the calling subscriber's line. The rotary line conductor 105 is again grounded once, 55 energizing the rotary line relay 130 of the connector D over a circuit that has been pointed out. The said rotary line relay then presses the springs 183 and 189 into contact, as previously explained, with the 60 result that the private magnet 133 is again energized. Energizing the private magnet 133 at this time produces one of two results, namely the release of the connector side switch from second to third position and es- 65 tablishing the desired connection, or the

busy release of the connector-switch if the desired line is busy. It will be understood, of course, that the busy release does not occur when a subscriber calls back on his own line, as will be explained. The busy release 70 follows only when a subscriber calls onto a line other than his own which is busy. The former result will be first considered, namely, the release of the connector side switch from second to third position. The release of the 75 side switch occurs when the private magnet 133 energizes, as heretofore explained. At the instant that the said side switch passes to third position, the connector side switch wipers 136 and 137, having engaged the contact points 194 and 195, extend the calling subscriber's line conductors into connection with the normal conductors 101 and 102. Since the said normal conductors 101 and 102 lead back to the calling line, it will be 80 evident that the calling subscriber has operated to connect the connector D with his own line. It will be remembered that when the line switch A first operated to close the bank springs 70 and 71 into contact, the 85 guarding potential was established over the private normal conductor 103 to the connector private bank contacts corresponding to the line allotted to the line switch A. One of the said contacts is now engaged by the 90 connector private wiper 128. Had the said guarding potential remained constantly on the said contact point, it would have been impossible for the connector side switch to have passed to third position, as described. 95 Instead, however, the said connector switch would have been released. Attention has been called to the fact that the energizing circuit for the connector rotary line relay 130 comprises the rotary private normal re- 100 lay 107, and, therefore that the said relay energizes in unison with the connector rotary line relay 130. That being the case, and since the guarding potential at the connector private bank contacts from the line 105 switch ground G' comprises the springs 110 and 111 of the said private normal relay 107, the guarding potential is interrupted at the same time that the connector rotary line relay 130 operates the private magnet 110 133. It is plain, therefore, that at the instant that the connector side switch passes to third position there is no guarding potential at the connector private bank contacts to interfere with the establishment of the 115 desired connection. The calling subscriber, having completed the call then proceeds to 120 signal the called substation #310.

125 In order to signal the called subscriber, the calling subscriber presses the signaling button 15, carrying the spring 16 into engagement with the grounded contact point 18. As a result the vertical line conductor 104 receives a current impulse from the substation ground G' through the substation 130

relay springs 22 and 23, ground springs 34 and 35 contact point 18, spring 16, thence through the springs 26 and 27 to the vertical line conductor 104. Grounding said conductor operates the connector vertical line relay 129 and also the differential relay 139 over circuits that have been pointed out. The operation of the said relays 139 and 129 causes the energization of the connector ringer relay 144 over the following circuit: from ground G^s at the connector through the line relay springs 182 and 182, private springs 184 and 185, side switch wiper 134, contact point 198, ringer relay 144, thence through the differential relay springs 200 and 199 to the battery lead 161, and through battery B to ground G. Since the differential relay 139 is energized, and said springs 199 and 200 are in contact, the energization of said ringer relay 144 bridges the ringer generator 151 across the normal conductors 101 and 102, whereby ringing current is projected over the line conductors 104 and 105 to the substation #310 for operating the ringer 202 at the said substation. It should be explained that the connector D, like all the connectors of the three hundred group, may be arranged to draw its ringing current from a ringer generator 151 that furnishes current of such character that only the ringer 202 of the substation #310 will be operated by said current, while the ringers of all other substations on the same line may be so tuned that they will not respond to the current from said generator. Similarly, the connectors of the two hundred group, which are employed when members of this group are called, may be arranged to draw their ringing current from a ringer generator that furnishes current of such character that only ringers tuned to respond to their current will be operated. Likewise, the connectors of the one hundred group may in turn draw their ringing current from still another generator that supplies current of such character that only those ringers that are correspondingly tuned will operate. It is evident, then, that when generator current is projected out on the line by the connector D of the three hundred group only the ringer 202 will be operatively affected. The path of the ringing current is as follows: from the ringer generator 151 through the ringer relay springs 150 and 149, side switch wiper 136, vertical normal conductor 101, vertical line conductor 104, condenser 196, ringer 202 at substation #310 back to the rotary line conductor 105, thence over the rotary normal conductor 102, ringer relay springs 146 and 147 to the ringer generator 151 again. The subscriber at substation #310 upon responding bridges his transmitter 203 and primary winding 204 of the induction-coil 205, in multiple with the transmitter 8 of the substation #110 and

the primary winding 11 of said substation, across the line conductors 104 and 105. When the connector side switch passes to third position, as explained in the foregoing, the battery B is bridged across the line for furnishing talking current thereto, and as soon as the dial of the calling substation comes to normal position the back-bridge relays 142 and 143 become energized over the following circuit: from ground G^s to the connector side switch contact point 201 (which latter has been engaged by the side switch wiper 135), through the side switch wiper 135, differential relay springs 206 and 207, rotary back-bridge relay 142, ringer relay springs 145 and 146, side switch wiper 137, contact point 195, rotary line-wiper 127, rotary normal conductor 102, rotary line conductor 105, springs 30 and 31, substation relay springs 21 and 20, transmitter 8, primary winding 11, contact point 17, spring 16, springs 26 and 27, vertical line conductor 104, vertical normal conductor 101, vertical line wiper 126, contact point 194, side switch wiper 136, ringer relay springs 149 and 148, vertical back-bridge coil 143 to the battery lead 161, and through battery B to ground G. The rotary back-bridge relay, upon energization, presses the springs 187 and 208 into engagement, thus connecting battery B across the same line over another circuit as follows: from ground G^s through the rotary back-bridge relay springs 208 and 187, ringer relay springs 153 and 152, winding 141 of the differential relay 139, rotary line relay 130 to the rotary trunk conductor 186, and through the selector C and line switch A to the rotary line conductor 105, thence through the substation #110, over circuits already explained, to the vertical line conductor 104, thence through the vertical line relay 129 of the connector D, and winding 140 of the differential relay 139 to the battery lead 161, thence through battery B to ground G. The called substation #310, of course, also draws current for talking from the line. Both of these circuits for supplying talking current are not necessary when the subscriber calls another subscriber on his own line, but it will be evident that they are necessary when he calls a subscriber on another line, in which case the first of said circuits which is thus controlled by the called subscriber is set up.

When the called subscriber answers he provides himself with talking battery current, and as a result the second circuit is then established, giving battery current to the calling subscriber upon the energization of the rotary back-bridge relay 142. When the called subscriber removes his receiver 209, as shown in Fig. 1, the switch-hook 210 upon rising permits the springs 211 and 212 and the springs 192 and 193 to engage before the springs 213 and 214 disengage, in

which case the substation relay 215 energizes over the following circuit: from the substation ground G^o to the conductor 216, thence through the springs 211 and 212, 5 springs 214 and 213, relay 215, transmitter 203, primary winding 204, springs 192 and 193, vertical conductor 104, vertical normal conductor 101, vertical wiper 126, side switch wiper 136, ringer relay springs 149 10 and 148, vertical back-ridge coil 143 to the battery lead 161, thence through battery B to ground G. From the said vertical line conductor 104 there leads a multiple circuit through the line switch bank springs 64 and 15 65, vertical private normal relay 106, vertical line relay 129 of the connector D, winding 140 of the differential-relay 139 to the battery lead 161. The substation relay 215, upon energizing, attracts and locks its armature in the same manner as described 20 in connection with substation relay 19. Had the calling subscriber called a subscriber on a different line, the former circuit would, of course, not exist, since in that 25 case the normal conductors 101 and 102 would not be in multiple with the line conductors 104 and 105. When the substation relay 215 energizes, the springs 217 and 218 separate and the springs 219 and 220 also 30 separate, the former two destroying the connection between the substation ground G^o and the ground spring 221, so that the said subscriber is deprived of the means for grounding either of the line conductors 104 or 105. 35 When the springs 219 and 220 separate, the normal circuit supplying current for the transmitter 203 is broken, and a circuit is substituted that comprises the winding of the substation relay coil 215. A normal circuit 40 supplying current for the transmitter 8 of the substation E extends from the rotary line conductor 105 through the springs 30 and 31 at said substation, to the springs 21 and 20 of the substation relay 19, thence 45 through the transmitter 8, primary winding 11, contact point 17, signaling spring 16, primary circuit springs 26 and 27 to the vertical line conductor 104. The springs 20 and 21 are, of course, similar to the springs 219 50 and 220 at the substation H, and it will be evident that the circuit for supplying the transmitter 203 of the answering subscriber with talking battery current is different from the circuit that supplies the transmitter 8 with talking battery. The circuit 55 for the said transmitter 203 extends from the vertical line conductor 104 through the primary circuit springs 193 and 192, primary winding 204, transmitter 203, substation relay 213, springs 213, 222 and 223 to the rotary line conductor 105. The voice-current conducting circuit through the substation E is the same as the circuit that supplies the transmitter 8 with current, and is 60 indicated by the heavy line conductors. At 65

the answering substation #310 the voice-current conducting circuit is different from the current-supplying circuit, and comprises the condenser 224, as indicated by the heavy conductors. The talking circuit at said substation #310 extends from the vertical line conductor 104 through the primary circuit springs 193 and 192, primary winding 204 of the induction-coil 205, transmitter 203 to the condenser 224, thence through the 70 springs 213, 222 and 223 to the rotary line conductor 105. If, while the subscribers #110 and #310 are conversing, the subscriber at substation #210 removes his receiver from the switch-hook, the substation 75 relay 225 is energized over similar circuits and locked in the same manner as the relay 215 of the substation #310. The effect of locking the said relay 225 produces the same results in connection with substation #210 80 that locking the relay 215 produces with respect to substation #310. The subscriber at substation #210 is, therefore, made powerless to interfere with the established connection, since his ground is cut off, as 85 explained in connection with substation #310. Of course, when the subscriber at the substation #210 hangs up his receiver the link 226 is carried down by the switch-hook, whereby the relay 225 is unlocked. 90 The same is true with respect to the substation #310 and the relay 215. After the subscribers are through talking, if the subscriber at the substation #110 hangs up his receiver he grounds his vertical and rotary 95 line conductors 104 and 105 simultaneously, thereby producing a release of the switches through the medium of which the connection has been established. As the switch-hook 3 descends, the release springs 36, 37 100 and 38 are pressed into contact, whereby the vertical and rotary line conductors are grounded, as stated. The primary result of grounding the rotary line conductor 105 is to unbalance the differential relay 139 by 105 shunting or short-circuiting the winding 141 between ground G^i at substation E and ground G^o at the connector D. 110 The shunting or short-circuiting branch may be traced from the substation ground 115 G^i through the substation relay springs 22 and 23 to the ground springs 34 and 35, thence to the release springs 36 and 37 to the rotary line conductor 105, line switch bank springs 66 and 67, private normal relay 107, first-selector side switch wiper 120, rotary shaft wiper 113, rotary line relay 130, winding 141 of the differential relay 139, ringer relay springs 152 and 153, rotary back-bridge relay springs 187 and 208 to 120 the side switch wiper 135, thence to ground G^o . The differential relay immediately energizes by the flow of current through the winding 140 by reason of the ground connection to the vertical line conductor 104. 125 130

The magnetizing current flows from substation ground G^1 to the ground release spring 36, thence through the release springs 37 and 38 to the vertical line conductor 104, line switch bank springs 64 and 65, private normal relay 106, first-selector side switch wiper 119, wiper 112, vertical line relay 129, winding 140 of the differential relay 139 to the battery lead 161, thence through battery B to ground G. When the differential relay 139, upon energizing, separates the springs 206 and 207, and carries the springs 199 and 200 into engagement. The former of said springs (namely the springs 206 and 207), as already explained, are included in the energizing circuit of the rotary back-bridge relay 142, so that as soon as the said springs separate, the said relay 142 deenergizes, whereby the spring 187 leaves the ground spring 208 and returns into engagement with the non-grounded battery spring 188. The effect of this last operation is to remove the shunt from the differential relay winding 141 and from the rotary line relay 130, as already described, establishing a circuit through said relay and winding, whereby a current-flow is set up in a reverse direction, further strengthening the differential relay 139 and reenergizing the rotary line relay 130. Under these conditions the line relays 129 and 130 are energized, whereby the trunk-release springs 227 and 228 are pressed into contact, while the differential relay springs 199 and 200 are in engagement, with the result that an energizing circuit is established through the release magnet 138 of the connector D in series with the back-release relay 125 of the selector C. The release magnet 138 of the connector, upon energization, restores the side switch L and the switch-shaft 126 to normal position in a manner fully described in connection with the connector disclosed in said Patent No. 815,176, at which time the line and private wipers 126, 127 and 128 are, of course, disconnected from the normal conductors 101, 102 and 103. The energizing of the back-release relay 125 carries the back-release relay springs 167 and 166 into engagement, as a result of energizing the release magnet 124 over a circuit extending from ground G^{13} through the said springs 167 and 166, and release magnet 124 to battery B. The selector release magnet, upon energizing, attracts its armature in readiness to release the switch when the release springs at the substation disengage, as described in connection with the selector disclosed in said Patent No. 815,321. The back-release relay 125 not only energizes the magnet 124, but also the release magnet 55 of the line switch A, since the said release magnet 55 is connected in multiple with the release magnet 124 of the selector A. The current through the said

release magnet 55 flows from the back-release relay spring 166 to the third trunk conductor 100, thence through the line switch bank springs 69 and 68, through said magnet 55 to the battery lead 161, and through battery B to ground G. When the release magnet 55 (Fig. 2) energizes, the armature 56 is attracted, whereby the armature 59 of the trip magnet 54 is raised and the hook terminal 73 latches the terminal 74 of the plunger arm 52, remaining thus in readiness to restore the individual switch when the release magnet 55 deenergizes sufficiently. As soon as the substation release springs 36, 37 and 38 separate, the energizing circuits of the rotary and vertical line relays 129 and 130 of the connector D are destroyed. As a result the energizing circuit through the release magnet 138 and the back-release relay 125 is broken, restoring the connector switch to normal condition. The deenergization of the back-release relay 125 in turn causes the deenergization of the selector release magnet, with the result already stated, and also causes the deenergization of the release magnet 55 of the line switch A. When the release magnet 55 of the said line switch deenergizes, the retracting spring 58, through the medium of the armatures 56 and 59, withdraws the plunger 51 from its operated condition into normal engagement with the plunger shaft 72, as a result destroying, of course, the energizing circuit of the cut-off relay 53, removing the guarding potential from the master switch bank K and from the connector banks, and disconnecting the subscriber's line from the first-selector. It will be clear, of course, that the private normal relays 106 and 107 will also be restored as soon as the line switch A is restored.

Upon a careful inspection it will become evident that the operations herein described are sufficient to enable those skilled in the art to understand how a connection can be established with a line other than that of the calling subscriber, in which case the connector wipers 126, 127 and 128 will establish connection with normal conductors other than the normal conductors 101, 102 and 103, which normal conductors will, of course, be allotted to the other line. In that event, when the called subscriber answers, as already explained, first the connector back-bridge or pole-changing relay 142 energizes when the called subscriber bridges his transmitter across the line, which relay in turn establishes a circuit for providing the transmitter of the calling subscriber with talking battery. In that case—that is, when the subscriber #110 is connected with a subscriber of some other line—if the subscriber #210 attempts to come in on the line the energizing circuit for the substation relay 225 does not comprise the normal conductors 125.

tors 101 and 102. It will be evident, furthermore, that the private normal relays 106 and 107 will play no part in connection with the calling connector, and that if the 5 subscriber #110 calls the other line while said line is busy, the private wiper 128 will find a guarding potential established at the connector private bank contact allotted to the desired line. In that case, and as already 10 explained in said connector patent, the connector side switch does not pass to third position, but is released, and the calling subscriber receives a busy signal.

The busy release occurs when the rotary 15 line conductor 105 is grounded for the last time and at the instant that the private magnet 133 is energized, at which time the private springs 229 and 230 are carried into engagement and an energizing circuit is established through the release magnet 138 20 as follows: from the private bank contact to the private wiper 128, side switch wiper 135, private springs 230 and 229, release magnet 138, differential relay springs 200 25 and 199 to the battery lead 161, thence through battery B to ground G. This last rotary impulse comes in while the side switch is in second position, and at the same time the differential relay 139 is energized 30 by the said rotary impulse, so that the differential relay springs 200 and 199 are in contact. After the connector is released, if the calling subscriber presses his signaling 35 button 15 he grounds the vertical line conductor and energizes the vertical line relay 129 of the connector and also raises the connector switch-shaft, which latter, upon rising, closes the off-normal springs 231 and 232, thereby establishing a busy-signal 40 through the calling substation. The busy signaling current flows from the secondary winding of the busy coil 154 through the off-normal springs 231 and 232 to the side switch wiper 137, thence through the condenser 45 233 to the calling substation and back over the vertical side of the line through the vertical line relay 129 to the battery lead 161 and back to the coil 154.

The condensers 234 and 233 are provided 50 in the connector for separating the calling section from the called section of the line at a point between the line relays 130 and 129 and the back-bridge relays 142 and 143 for well-known reasons. When the calling 55 subscriber hears the busy signal he hangs up his receiver which operation grounds both of the line conductors 104 and 105 and simultaneously energizes the vertical and rotary line relays 129 and 130 and the differential relay 139, with the result already explained—that is, with the result that all of the switches are released and restored to normal condition. Suppose that the substation #110 is called by another substation, #120 for example. Assume that the

line switch allotted to the line #120 seizes the trunk line leading to the first-selector C, and assume also that the connector D is of the one hundred group and is the one selected by the first-selector C. The established connection would then be the same as that shown in Fig. 1, except that the trunk line leading to the connector D would be connected with the line switch allotted to the line #120 instead of with the line switch A, as shown. In that case, if a subscriber located on the line (as the subscriber #210 is located) were to remove his receiver and attempt to make a call while the line is busy, the relay 225 would, of course, be energized over a circuit including the vertical normal conductor 101 and the vertical back-bridge coil 143 to the battery B. When one subscriber has called another line, the release is the same as the release already described, and connection with the called line is severed as soon as the connector wipers are disengaged from the banks.

From the foregoing it will be seen that we provide an improved telephone system 90 which is an improvement on prior application Serial #270,591, filed July 20, 1905, and in which are combined a common battery and a lock-out and individual switch arrangements for the party lines. Furthermore, we provide a lock-out relay energizing circuit which includes the transmitter and which includes three switch points controlled by the switch-hook, two of the points (springs 26 and 27 and springs 28 and 29) 100 being normally open and the other one (springs 32 and 33) being normally closed. This energizing circuit also includes the subscriber's ringing key, by which the calling subscriber initiates the operations which result in the production of a call-signal at the called subscriber's substation. It will also be seen that two private normal relays are employed in each subscriber's individual switch, for the purposes set forth, which relays are each bridged by a condenser.

What we claim as our invention is:—

1. The combination of a plurality of party line substations, lock-out devices for the party line substations, a common battery 115 for supplying talking current to the party line substations, an automatic individual switch allotted to the party line substations, a plurality of first-selectors, and trunk lines leading from the individual switch to the 120 first-selectors.

2. The combination of party line substations each provided with a lock-out relay and a microphone transmitter, and with a hook-switch having three switch points, two 125 of said points being normally open and the third being normally closed, and a lock-out relay energizing circuit including the said transmitter and three switch points.

3. In a telephone system, a party-line, a 130

plurality of party line substations thereon, a subscriber's ringing key for each party line substation, a lock-out relay for each party line substation, and a lock-out relay 5 energizing circuit for each substation including the ringing key thereof, said relays connected to only one side of the line.

4. The combination of a subscriber's telephone line, an individual trunking switch 10 for said line, a plurality of first-selectors, trunk lines leading from the individual switch to the first-selectors, and a plurality of private normal relays in each of said trunk lines.

15 5. The combination of a plurality of party line substations, lock-out devices for the party line substations, a common battery for supplying talking current to the party line substations, an automatic individual switch 20 allotted to the party line substations, a plurality of first-selectors, trunk lines leading from the individual switch to the first-selectors, and automatic connectors less in number than the subscribers and each controllable by a calling subscriber for closing the final connection with the called subscriber's line.

6. The combination of party line substations each provided with a lock-out relay 30 and a microphone transmitter, and with a hook-switch having three switch points, two of said points being normally open and the third being normally closed, a lock-out relay energizing circuit including the said transmitter and three switch points, and automatic connectors less in number than the subscribers and each controllable by a calling subscriber for closing the final connection with the called subscriber's line.

40 7. The combination of party line substations, a subscriber's ringing key for each party line substation, a lock-out relay for each party line substation, a lock-out relay energizing circuit for each substation including the ringing key thereof, and automatic connectors less in number than the subscribers and each controllable by a calling subscriber for closing the final connection with the called subscriber's line.

50 8. The combination of a subscriber's telephone line, an individual trunking switch for said line, a plurality of first-selectors, trunk lines leading from the individual switch to the first-selectors, a plurality of 55 private normal relays in each of said trunk lines, and automatic connectors less in number than the subscribers and each controllable by a calling subscriber for closing the final connection with the called subscriber's line.

60 9. The combination of a plurality of party line substations, lock-out devices for the party line substations, a common battery for supplying talking current to the party line 65 substations, an automatic individual pro-

gressively movable non-numerical switch allotted to the party line substations, a plurality of automatic switches, and trunk lines leading from the individual switch to the automatic switches.

70

10. The combination of a subscriber's telephone line, an individual trunking switch for said line, a plurality of automatic switches, trunk lines leading from the individual switch to the automatic switches, 75 and a plurality of relays associated with each trunk line for controlling the private normal circuit.

75

11. The combination of a plurality of party line substations, lock-out devices for 80 the party line substations, a common battery for supplying talking current to the party line substations, an automatic individual progressively movable non-numerical switch allotted to the party line substations, connecting apparatus, and trunk lines leading from the individual switch to the connecting apparatus.

85

12. The combination of a subscriber's telephone line, an individual trunking switch 90 for said line, connecting apparatus, trunk lines leading from the individual switch to the connecting apparatus, and a plurality of relays associated with each trunk line for controlling the private normal circuit.

95

13. An automatic party line telephone exchange system, comprising common battery talking means, preliminary impulse means, trunks and automatic means for selecting them ahead of the calls, means responsive to the preliminary impulse for seizing the preselected trunks, and party-line lock-out means, substantially as set forth.

100

14. In a system in which the trunks are divided into groups, the combination of a 105 plurality of party line substations, lock-out devices for the party line substations, a common battery for supplying talking current to the party line substations, an automatic individual switch allotted to the party line substations, a plurality of first selectors, each selector having vertical motion to select groups and rotary motion to find an idle trunk in any selected group, and trunk lines 110 leading from the individual switch to the first selectors.

110

15. In a system in which the subscribers' lines are divided into groups, the combination of party line substations each provided with a lock-out relay and a microphone transmitter, and with a hook-switch having three switch points, two of said points being normally open and the third being normally closed, a lock-out relay energizing circuit including the said transmitter and three switch points, and means having vertical motion to select groups and rotary motion to find the line of the called subscriber.

120

16. In a system in which the subscribers' lines are divided into groups, the combina- 130

- tion of party line substations, a subscriber's ringing key for each party line substation, a lock-out relay for each party line substation, a lock-out relay energizing circuit for each 5 substation including the ringing key thereof, and means having vertical motion to select groups and rotary motion to find the line of the called subscriber.
17. In a system in which the trunks are divided into groups, the combination of a subscriber's telephone line, an individual trunking switch for said line, a plurality of first selectors, each selector having vertical motion to select groups and rotary motion to 10 find an idle trunk in any selected group, trunk lines leading from the individual switch to the first selectors, and a plurality of private normal relays in each of said trunk lines.
18. In a system in which the trunks are divided into groups, the combination of a plurality of party line substations, lock-out devices for the party line substations, a common battery for supplying talking current 15 to the party line substations, an automatic individual switch allotted to the party line substations, a plurality of first selectors, each selector having vertical motion to select groups and rotary motion to find an idle 20 trunk in any selected group, trunk lines leading from the individual switch to the first selectors, and automatic connectors less in number than the subscribers and each controllable by a calling subscriber for finding 25 the called subscriber's line.
19. In a system in which the subscribers' lines are divided into groups, the combination of party line substations each provided with a lock-out relay and a microphone 30 transmitter, and with a hook-switch having three switch points, two of said points being normally open and the third being normally closed, a lock-out relay energizing circuit including the said transmitter and three switch 35 points, and automatic connectors less in number than the subscribers and each having vertical and rotary motion controllable by a calling subscriber for finding the group and line of the called subscriber.
20. In a system in which the subscribers' lines are divided into groups, the combination of party line substations, a subscriber's ringing key for each party line substation, a lock-out relay for each party line substation, a lock-out relay energizing circuit for each 40 substation including the ringing key thereof, and automatic connectors less in number than the subscribers and each having vertical and rotary motion controllable by a calling subscriber for finding the group and line of the called subscriber.
21. In a system in which the subscribers' lines are divided into groups, the combination of a subscriber's telephone line, an individual trunking switch for said line, a plu- 45
- rality of first selectors, trunk lines leading from the individual switch to the first selectors, a plurality of private normal relays in each of said trunk lines, and automatic connectors less in number than the subscribers 50 and each having vertical and rotary motion controllable by a calling subscriber for finding the group and line of the called subscriber.
22. In a system in which the lines are divided into groups, the combination of a plurality of party line substations, lock-out devices for the party line substations, a common battery for supplying talking current 55 to the party line substations, an individual progressively movable non-numerical switch allotted to the party line substations, a plurality of automatic switches, each automatic switch having vertical motion to select groups and rotary motion to find a line in 60 any selected group, and trunk lines leading from the individual switch to the automatic switches.
23. In a system in which the lines are divided into groups, the combination of a subscriber's telephone line, an individual trunking switch for said line, a plurality of automatic switches, trunk lines leading from the individual switch to the automatic switches, each automatic switch having vertical motion to select groups and rotary motion to find a line in any selected group, 65 and a plurality of relays associated with each trunk line for controlling the private normal circuit.
24. In a system in which the trunks and subscribers' lines are divided into groups, the combination of a plurality of party line substations, lock-out devices for the party line substations, a common battery for supplying talking current to the party line substations, an automatic individual progressively movable non-numerical switch allotted to the party line, connecting apparatus, and trunk lines leading from the individual switch to the connecting apparatus, said connecting apparatus having vertical motion to find groups and rotary motion to 70 find idle trunks and called lines.
25. In a system in which the trunks and subscribers' lines are divided into groups, the combination of a subscriber's telephone line, an individual trunking switch for said line, connecting apparatus, trunk lines leading from the individual switch to the connecting apparatus, and a plurality of relays associated with each trunk line for controlling the private normal circuit, said connecting apparatus having vertical motion to find groups and rotary motion to find idle 75 trunks and called lines.
26. An automatic party line telephone exchange system, comprising common battery talking means, preliminary impulse means, trunks and automatic means for selecting 80

- them ahead of the calls, means responsive to the preliminary impulse for seizing the preselected trunks, means having both vertical and rotary motion for extending the connection from a selected trunk, and party line lock-out means, substantially as set forth.
27. In a telephone system, a party line, a lock-out arrangement therefor adapted to prevent interference between subscribers on the same line, common battery means for supplying current to the line for talking purposes, and a non-numerical trunking switch for said line subject to control by any calling subscriber thereon for trunking the call in the direction of the called subscriber.
28. In a telephone system, a party line, lock-out relays for the substations thereon adapted to prevent interference between subscribers on the same line, a non-numerical trunking switch for said line subject to control by any subscriber thereon, and common battery means for supplying current to the line for talking purposes.
29. In a telephone system, a party line, means for preventing interference between the subscribers on said line, trunks and means for selecting them ahead of the calls, means for supplying current to the line for talking purposes, and means whereby any calling subscriber on the line closes connection with a preselected trunk line.
30. In a telephone system, a party-line provided with means for preventing interference between the subscribers thereon, a non-numerical trunking switch for said line, first and second selectors, and a connector, all controllable over said line by any subscriber thereon.
31. In a telephone system, a subscriber's line, a non-numerical switch individual to said line, a plurality of trunk lines extending from said switch, a pair of relays included in said trunk lines, a ground connection for providing a guarding potential for said subscriber's line, and means whereby said relays control said ground connection.
32. In a telephone system, a subscriber's line, a non-numerical switch individual to said line, a plurality of trunk lines extending from said switch, a pair of relays included in said trunk lines, a condenser in shunt of each of said relays, a ground connection for providing a guarding potential for said subscriber's line, and means whereby said relays control said ground connection.
33. In a telephone system, a talking circuit including a subscriber's line, a non-numerical switch individual thereto, a pair of line wipers and a private normal wiper controlled by said switch, and a pair of relays serially included in the talking circuit for controlling a ground connection over said private normal conductor.
34. In a telephone system, a talking circuit including a subscriber's line, a non-numerical switch individual thereto, a pair of line wipers and a private normal wiper controlled by said switch, a pair of relays serially included in the talking circuit for controlling a ground connection over said private normal conductor, and a condenser in shunt of each of said relays to permit the passage of talking current therethrough.
35. In a telephone system, a telephone line, a plurality of sub-stations for said line, a lock-out relay for each telephone for preventing one telephone from interfering with another, a separate energizing circuit for each relay, and an operating circuit for each telephone, the lock-out relay of each telephone controlling the operating circuit of its telephone, and a non-numerical switch associated with the line controlling the circuits of all of the lock-out relays.
36. In a telephone system, a telephone line, a plurality of sub-stations for said line, a lock-out relay for each telephone for preventing one telephone from interfering with another, a separate energizing circuit for each relay, and an operating circuit for each telephone, the lock-out relay of each telephone controlling the operating circuit of its telephone, and a non-numerical progressively movable switch associated with the line controlling the circuits of all the lock-out relays.
37. In a telephone system, a telephone line, a plurality of sub-stations for said line, a lock-out relay for each telephone for preventing one telephone from interfering with another, a separate energizing circuit for each relay, and an operating circuit for each telephone, the lock-out relay of each telephone controlling the operating circuit of its telephone, and a progressively movable non-numerical switch associated with the line and controlled over the operating circuit at each telephone controlling the circuits of all of the lock-out relays.
38. In a telephone system, a telephone line, a plurality of sub-stations for said line, a lock-out relay for each telephone for preventing one telephone from interfering with another, a common battery for supplying talking current to the substations on said line, a progressively movable non-numerical switch associated with said line controlling the energizing circuits of said relays, and means at each telephone for operating said switch to prepare an energizing circuit for a plurality of said relays.
39. In a telephone system, a line, a plurality of telephones for said line, a lock-out magnet at each telephone controlling an operating circuit for its telephone, a non-numerical progressively movable switch for serially included in the talking circuit for

the line, an energizing circuit at each telephone for the lock-out magnet associated therewith, a branch common to all of said circuits and controlled by said switch, means

5 at each telephone for operating said switch to close said common branch to prepare an energizing circuit for the lock-out magnets associated with said line, whereby they may be operated during a call, and means for 10 rendering the lock-out magnet of the calling telephone inoperative during the same call.

40. In a telephone system, a line, an automatic progressively movable non-numerical switch for said line, a plurality of telephones 15 for said line, an impulse sender for each telephone for operating said switch over said line, an electromagnetic lock-out mechanism for each telephone for rendering its impulse sender inoperable, and a common 20 battery for supplying talking current to the telephones on said line.

41. In a telephone system, a line, an automatic progressively movable non-numerical switch for said line, a plurality of telephones 25 for said line, an impulse sender for each telephone for operating said switch over said line; an electromagnetic lock-out mechanism for each telephone for rendering its impulse sender inoperable after any other 30 telephone on the line is operated, and a common battery for supplying talking current to the telephones on said line.

42. In a telephone system, a line, an automatic progressively movable non-numerical 35 switch for said line, a plurality of telephones for said line, an impulse sender for each telephone for operating said switch over said line, an electromagnetic lock-out mechanism for each telephone for rendering 40 its impulse sender inoperable only after another telephone is operated, and a common battery for supplying talking current to the telephones on said line.

43. In a telephone system, a line, an automatic progressively movable non-numerical 45 switch for said line, a plurality of telephones for said line, an impulse sender for each telephone for operating said switch over said line, an electromagnetic lock-out 50 device for each telephone, a circuit for each lock-out controlled by the switch, each lock-out when operated rendering the impulse sender of its telephone inoperative, and a common battery for supplying talking current 55 to the telephones on said line.

44. In a telephone system, a line, an automatic progressively movable non-numerical switch for said line, a plurality of telephones for said line, an impulse sender for each telephone for operating said switch over said line, an electromagnetic lock-out device for each telephone, a circuit for each lock-out controlled by the switch, each lock-out when operated rendering the impulse 60 sender of its telephone inoperative after any

other telephone has operated the switch, and a common battery for supplying talking current to the telephones on said line.

45. In a telephone system, a line, an automatic progressively movable non-numerical 70 switch for said line, a plurality of telephones for said line, an impulse sender for each telephone for operating said switch over said line, an electromagnetic lock-out device for each telephone, a circuit for each lock-out 75 controlled by the switch, each lock-out when operated rendering the impulse sender of its telephone inoperative only after any other telephone has operated the switch, and a common battery for supplying talking current 80 to the telephones on said line.

46. In a telephone system, a line, an automatic progressively movable non-numerical switch for said line, a plurality of telephones for said line, an impulse sender for each telephone for operating said switch over said line, an electromagnetic lock-out device for each telephone, a circuit for each lock-out controlled by the switch and the telephone, and a common battery for supplying talking 85 current to the telephones on said line.

47. In a telephone system, a line, an automatic progressively movable non-numerical switch for said line, a plurality of telephones for said line, an impulse sender for each telephone for operating said switch over said line, an electromagnetic lock-out device for each telephone, a circuit for each lock-out controlled by the switch and the telephone only after another telephone has operated 90 the switch, and a common battery for supplying talking current to the telephones on said line.

48. In a telephone system, a line, an automatic progressively movable non-numerical 105 switch for said line, a plurality of telephones for said line, an impulse sender for each telephone for operating said switch over said line, an electromagnetic lock-out mechanism for each telephone for rendering its impulse 110 sender inoperable, a normally inoperative circuit common to all said lock-out devices controlled by said switch and rendered operative when the switch is operated, and an individual branch for each lock-out controlled by its associated telephone to operate the lock-out after the switch has operated, and a common battery for supplying talking 115 current to the telephones on said line.

49. In a telephone system, a line, an automatic progressively movable non-numerical switch for said line, a plurality of telephones for said line, an impulse sender for each telephone for operating said switch over said line, an electromagnetic lock-out mechanism 120 for each telephone for rendering its impulse sender inoperable, a normally open circuit common to all said lock-out devices controlled by said switch to close the same when the switch is operated, an individual branch 125

65 sender of its telephone inoperative after any 130

for each lock-out controlled by its associated telephone to operate the lock-out after the switch has closed the circuit, and a common battery for supplying talking current to the telephones on said line.

5. 50. In a telephone system, a line, an automatic progressively movable non-numerical switch for said line, a plurality of telephones for said line, an impulse sender for each telephone for operating said switch over said line, an electromagnetic lock-out mechanism for each telephone for rendering its impulse sender inoperable, a normally open circuit common to all said lock-out devices controlled by said switch to close the same when the switch is operated, a normally open individual branch for each lock-out mechanism controlled by its associated telephone to close an energizing circuit for the lock-out mechanism after the switch is operated, said common circuit comprising the line, and a common battery for supplying talking current to the telephones on said line.

10. 51. In a telephone system, a line, an automatic progressively movable non-numerical switch for said line, a plurality of telephones for said line, an impulse sender for each telephone for operating said switch over said line, an electromagnetic lock-out mechanism for each telephone for rendering its impulse sender inoperable, a normally inoperative circuit common to all said lock-out devices controlled by said switch, and rendered operative when the switch is operated, an individual branch for each lock-out controlled by its associated telephone to operate the lock-out after the switch has operated, said common circuit comprising the line, and a common battery for supplying talking current to the telephones on said line.

15. 52. In a telephone system, a line, an automatic progressively movable non-numerical switch for said line, a plurality of telephones for said line, an impulse sender for each telephone for operating said switch over said line, an electromagnetic lock-out mechanism for each telephone for rendering its impulse sender inoperable, a normally open circuit common to all said lock-out devices controlled by said switch to close the same when the switch is operated, an individual branch for each lock-out controlled by its associated telephone to operate the lock-out after the switch has closed the circuit, said common circuit comprising the line, and a common battery for supplying talking current to the telephones on said line.

20. 53. In a telephone system, a line, an automatic progressively movable non-numerical switch for said line, a plurality of telephones for said line, an impulse sender for each telephone for operating said switch over said line, an electromagnetic lock-out mechanism for each telephone for render-

ing its impulse sender inoperable, a normally open circuit common to all said lock-out devices controlled by said switch to close the same when the switch is operated, a normally open individual branch for each lock-out mechanism controlled by its associated telephone to close an energizing circuit for the lockout mechanism after the switch is operated, said common circuit comprising the line, and a common battery for supplying talking current to the telephones on said line.

25. 54. In a telephone system, a line, an automatic progressively movable non-numerical switch for said line, a plurality of telephones for said line, an impulse sender for each telephone for operating said switch over said line, an electromagnetic lock-out mechanism for each telephone for rendering its impulse sender inoperable, a normally inoperative circuit common to all said lock-out devices controlled by said switch and rendered operative when the switch is operated, an individual branch for each lock-out controlled by its associated telephone to operate the lock-out after the switch has operated, said common circuit comprising only one side of the line, and a common battery for supplying talking current to the telephones on said line.

30. 55. In a telephone system, a line, an automatic progressively movable non-numerical switch for said line, a plurality of telephones for said line, an impulse sender for each telephone for operating said switch over said line, an electromagnetic lock-out mechanism for each telephone for rendering its impulse sender inoperable, a normally open circuit common to all said lock-out devices controlled by said switch to close the same when the switch is operated, an individual branch for each lock-out controlled by its associated telephone to operate the lock-out after the switch has closed the circuit, said common circuit comprising only one side of the line, and a common battery for supplying talking current to the telephones on said line.

35. 56. In a telephone system, a line, an automatic progressively movable non-numerical switch for said line, a plurality of telephones for said line, an impulse sender for each telephone for operating said switch over said line, an electromagnetic lock-out mechanism for each telephone for rendering its impulse sender inoperable, a normally open circuit common to all said lock-out devices controlled by said switch to close the same when the switch is operated, a normally open individual branch for each lock-out mechanism controlled by its associated telephone to close an energizing circuit for the lock-out mechanism after the switch is operated, said common circuit comprising only one side of the line, and a common bat-

tery for supplying talking current to the telephones on said line.

57. In a telephone system, a line, an automatic progressively movable non-numerical switch for said line, a plurality of telephones for said line, an impulse sender for each telephone for operating said switch over said line, an electromagnetic lock-out mechanism for each telephone for rendering its impulse sender inoperable, a circuit common to all of said lock-out mechanisms controlled by said switch, an individual branch for each lock-out mechanism controlled by its associated telephone, and a common battery for supplying talking current to the telephones on said line.

58. In a telephone system, a line, an automatic progressively movable non-numerical switch for said line, a plurality of telephones for said line, an impulse sender for each telephone for operating said switch over said line, an electromagnetic lock-out mechanism for each telephone for rendering its impulse sender inoperable, a circuit common to all of said lock-out mechanisms controlled by said switch, an individual branch for each lockout mechanism controlled by its associated telephone, said common circuit individual to the line, and a common battery for supplying talking current to the telephones on said line.

59. In a telephone system, a line, an automatic progressively movable non-numerical switch for said line, a plurality of telephones for said line, an impulse sender for each telephone for operating said switch over said line, an electromagnetic lock-out mechanism for each telephone for rendering its impulse sender inoperable, a circuit common to all of said lock-out mechanisms controlled by said switch, an individual branch for each lockout mechanism controlled by its associated telephone, said common circuit individual to one side of the line, and a common battery for supplying talking current to the telephones on said line.

60. In a telephone system, a line, an automatic progressively movable non-numerical switch for said line, a plurality of telephones for said line, an impulse sender for each telephone for operating the switch over said line, an electromagnetic lock-out mechanism for each telephone, for rendering its impulse sender inoperable, a circuit common to all of said lock-out mechanisms controlled by said switch, an individual branch circuit for each lock-out mechanism con-

trolled by its telephone whereby when the first telephone comes on the line to operate the switch its lockout does not operate, and whereby the other lock-out devices are rendered operable when any other telephone is brought on the line, whereby said other telephone is prevented from interfering, if its impulse mechanism is operated, with the connection of the telephone previously on the line, and a common battery for supplying talking current to the telephones on said line.

61. The combination of a subscriber's telephone line, an individual trunking switch for said line, a plurality of automatic switches, trunk lines leading from the individual switch to the automatic switches, and a plurality of relays in each trunk line for controlling the private normal circuit.

62. The combination of a subscriber's telephone line, an individual trunking switch for said line, connecting apparatus, trunk lines leading from the individual switch to the connecting apparatus, and a plurality of relays in each trunk line for controlling the private normal circuits.

63. In a system in which the lines are divided into groups, the combination of a subscriber's telephone line, an individual trunking switch for said line, a plurality of automatic switches, trunk lines leading from the individual switch to the automatic switches, each automatic switch having vertical motion to select groups and rotary motion to find a line in any selected group, and a plurality of relays in each trunk line for controlling the private normal circuit.

64. In a system in which the trunk lines and subscribers' lines are divided into groups, the combination of a subscriber's telephone line, an individual trunking switch for said line, connecting apparatus, trunk lines leading from the individual switch to the connecting apparatus, and a plurality of relays in each trunk line for controlling the private normal circuit, said connecting apparatus having vertical motion to find groups and rotary motion to find idle trunk lines and called lines.

Signed by us at Chicago, Cook county, Illinois, this 15th day of December, 1906.

ALEXANDER E. KEITH.
